(57) **CLAIM**

I claim the ornamental design for a see through dome mount, as shown and described.

DESCRIPTION

FIG. 1 is a back side view of the see through dome mount showing my new design;

FIG. 2 is a right side view of the see through dome mount;

FIG. 3 is a front side view of the see through dome mount;

FIG. 4 is a left side view of the see through dome mount;

FIG. 5 is a top side view of the see through dome mount;

FIG. 6 is a bottom side view of the see through dome mount;

FIG. 7 is a bottom-right-back perspective view of the see through dome mount;

FIG. 8 is a top-right-back perspective view of the see through dome mount;

FIG. 9 is a top-left-back perspective view of the see through dome mount;

FIG. 10 is another bottom-right-back perspective view of the see through dome mount;

FIG. 11 is a top-right-front perspective view of the see through dome mount;

FIG. 12 is a bottom-right-front perspective view of the see through dome mount; and,

FIG. 13 is another top-right-front perspective view of the see through dome mount.
